UNITED STATES PATENT OFFICE.

EDWARD F. REYNOLDS, OF SANTA BARBARA, CALIFORNIA.

GAS ENGINE.

Application filed August 13, 1923. Serial No. 657,117.

To all whom it may concern:

Be it known that I, EDWARD F. REYNOLDS, a citizen of the United States, residing at Santa Barbara, in the county of Santa Barbara and State of California, have invented certain new and useful Improvements in Gas Engines, of which the following is a specification.

This invention relates to an internal explosion or combustion engine and more particularly to the two-cycle engine type.

The primary object of the invention is the provision of an internal combustion or explosion engine, wherein the cylinder is provided with two oppositely driven pistons connected to the crank shaft so that when a charge is ignited between said pistons increased power will be produced and communicated to said shaft.

Another and very important object of the invention is the production of a two-cycle engine, having oppositely moving pistons therein connected to the common crank shaft, said engine being devoid of head gears or cams, the intake and exhaust ports being opened and closed by the pistons at each revolution.

Another and still important object of the invention is the construction of a two-cycle engine, which is extremely light, highly efficient in operation, practical, durable, easily assembled, yet permitting the parts to be replaced when so desired and otherwise capable of being manufactured at a very low cost whereby its commercial possibilities are greatly enhanced.

The invention will be best understood from a consideration of the following detailed description taken in connection with the accompanying drawing forming a part of this specification, with the understanding, however, that the invention is not confined to any strict conformity with the showing in the drawing, but may be changed and modified so long as such changes and modifications mark no material departure from the salient features of the invention as expressed in the subject matter being claimed.

I attain these objects and others in the accompanying drawing, wherein:

Figure 1 is a vertical, longitudinal section through the engine.

Figure 2 is a vertical section taken on the line 2—2 of Fig. 1.

Figure 3 is a section showing the posi-

tion of the piston when the intake port is open; and

Figure 4 is a similar view showing the exhaust port open.

Referring now to the drawings wherein like reference characters designate corresponding parts throughout the several views, 5 designates the upper cylinder casing, having an enlarged central portion 6 and base portion 7, to which the crank case 8 is connected in the usual manner. The cylinder proper 9 is provided with an upper piston 10 and a lower piston 11, between which the combustion chamber 12 may receive an explosive charge to be ignited by suitable ignition means, such as a spark plug insertible in the spark plug opening 13, as clearly shown by Figure 2 of the drawing.

The upper piston 9 is connected by two connecting rods 14 to the crank shaft 15, operable in suitable bearings 16, and the lower piston 11 is connected by a single connecting rod 17 to the said crank shaft, whereby when a charge of compressed fuel is ignited in the combustion chamber 1, the upper piston moves upwardly and the lower piston moves downwardly, pulling up and pushing down on the crank shaft 15 and consequently turning the same. The said connecting rods 14 are attached to the bottom part or skirt 18 which acts as a shoulder for compressing the fuel in the fuel mixing chamber 19. The pump compression chamber 19 communicates with the by-path chambers 20, through the port 22, said chambers holding the fuel and air until it has been admitted into the cylinder or combustion chamber 12 where it is ignited.

The valves are piston operated, being opened and closed as the said pistons pass the inlets and exhaust ports. It will be thus observed that the upper piston 10 is provided with horizontal ports 23 and that the walls of the cylinder is correspondingly provided with ports 24, which register with said ports 23 to permit of the exhaust through the passage or opening 25 in the casing. Four of such ports are provided in the said piston and cylinder and are consequently opened and closed at each operation of the same.

There are also provided four ports 26 and four corresponding ports 27 in the lower wall of the cylinder and bottom part of the piston skirt 28, which admits the charge of

compressed air and gas for the scavenger and fuel intake, which passes through said ports from the remittance chambers 20, 21 and confines the mixture until it has been admitted into the cylinder or combustion chamber 12. The mixing chamber 19 compresses the fuel from the remittance chambers by means of the piston portion 18, above referred to, it being observed that a head chamber 30, over the upper piston, admits of the scavenging by the burnt gases after each explosion, the air being compressed by the piston 11, moving upward which forces the air into the tube or mani-fold 30^a and passes it into a by-path chamber and at the end of the piston stroke it is admitted into the cylinder or combustion chamber 1 through the ports 26, 27, which are opened at this instant. The fuel is taken into the mixing chamber 6 and is compressed up into the chamber 20, as the upper piston moves upwardly, whereupon the ports 32 are opened by the moving piston a few degrees after the ports 34 discharge the compress gas or fuel into the combustion chamber, whereupon the charge is then ready to be compressed by the pistons when they are moved toward each other. When this compression takes place the fuel is then ready to be ignited by means of the spark plug in the opening 13, as clearly shown. A cooling chamber 34 is also provided to increase its efficiency to perform the functions above set forth.

35 The invention will be best understood from a consideration of the following detailed description taken in connection with the accompanying drawing forming a part

of this specification, with the understanding, however, that the invention is not confined to any strict conformity with the showing in the drawing, but may be changed and modified so long as such changes and modifications mark no material departure from the salient features of the invention as expressed in the subject matter being claimed. 40 45

Having thus described and illustrated my invention, what I claim as new and desire to secure by Letters Patent is: 50

In an internal combustion engine of the two-cycle type, a cylinder provided with an enlarged base portion and an enlarged head chamber, an air and a fuel chamber surrounding the cylinder having ports communicating therewith, a pair of oppositely disposed pistons reciprocately mounted in the cylinder, one of the pistons having a skirt for receiving the other piston and provided with ports for controlling the entrance of air and fuel into the cylinder through the ports of the air and fuel chambers, a port in the fuel chamber communicating with the enlarged base portion of the cylinder, an enlargement formed on the skirt for acting on the fuel in the fuel chamber, a tube connecting the head chamber with the air chamber, a crank shaft and means connecting the pistons with the crank shaft. 55 60 65

In testimony whereof I affix my signature in presence of two witnesses.

EDWARD F. REYNOLDS.
